UNITED STATES PATENT OFFICE.

JOHN HOWARD WAY, OF PHILADELPHIA, PENNSYLVANIA.

DESIGN FOR A CHEST AND NECK PROTECTOR.

SPECIFICATION forming part of **Design No. 27,926**, dated **November 30, 1897**.

Application filed September 13, 1897. Serial No. 651,548. Term of patent 3½ years.

To all whom it may concern:

Be it known that I, JOHN HOWARD WAY, a citizen of the United States, and a resident of the city of Philadelphia, in the State of Pennsylvania, have produced a new and original Design for a Chest and Neck Protector, of which the following is a specification, reference being had to the accompanying drawing.

- 5 10 My invention relates to a new and original design for chest and neck protectors, which is represented in the accompanying drawing, in which the figure represents a front view thereof.
- 15 The leading feature of my design consists in a chest and neck protector of the shape and configuration shown and described. Its

upper edge *a* is straight. The side edges *b* and lower edge *f* are rounded, as shown in the drawing, with a sharp reentrant angle *c* 20 upon each side. From the top corners to the beginning of these reentrant angles the contour of the sides is straight, as shown at *d*. The upper edges *g* of the two reentrant angles are straight, while the lower edges *e* are 25 inclined.

I claim—

The design for a chest and neck protector substantially as shown and described.

JOHN HOWARD WAY.

Witnesses:

JAMES H. BELL,
E. REESE.
